UNITED STATES PATENT OFFICE.

REGINALD BASHAM, OF ONEHUNGA, NEW ZEALAND.

DRAFT AND RAIN EXCLUDER ATTACHMENT FOR DOORS.

Application filed June 9, 1924. Serial No. 718,887.

This invention has for its object the provision of an improved construction of draft and rain excluding attachments for doors, of the class in which a batten is mounted on 5 the door to extend along its bottom, and is adapted to rise and fall while maintaining a horizontal position, and to be lowered when the door is closed, and thus to engage the floor and cover the crack beneath it, and 10 then to be raised as the door is opened and thereby to free the floor so that the door may swing freely.

The invention relates more particularly to that known class of device in which the 15 excluder batten is attached to the face of the door by means of pivoted links that allow for the batten moving up and down, parallel ruler fashion, maintaining its parallel level with the door bottom but moving longitudinally on the door, and in which the batten 20 is adapted to be lifted to the raised position with one end projecting beyond the hinge edge of the door, by means of a spring, when the door is opened. Then on the 25 closing of the door, the said projecting end will engage the door frame and the batten will be forced lengthwise and downwards against such spring's action, to engage the floor with its bottom edge.

The invention consists in a special construction of batten and spring and in the particular arrangement of these parts in the fitting of the attachment to the door.

These features are illustrated in the accompanying drawings, in which:

Figure 1 is a face view of a door with the attachment shown mounted thereon and in the raised position.

Figure 2 is an enlarged detail view of the operating parts of the attachment.

Figure 3 is a cross section thereof taken on the line 3—3 of Figure 2.

In carrying out the invention, the door A is formed with a rebate B along the inside of its bottom edge, of sufficient height and depth inwards from the surface of the door to provide for the batten C being fitted neatly within it when it is in the raised position. The batten is made of a length corresponding to the width of the door and 45 it is held within the said rebate by means of two or more links D, one end of each of which is pivotally attached to the surface of the door above the rebate and the other 50 similarly attached to the face of the batten. These links D are so disposed and are made

of such a length that the batten may move, parallel ruler fashion, up and down with relation to the door, so that in the up position it will clear the floor, and in the down position it will engage the floor surface. The lower edge of the batten may be provided with a rubber or other cushion edging C' to ensure of an airtight engagement being effected.

The batten C is also so disposed in its length along the door width that, when in the raised position, the end adjacent to the hinge edge of the door will project a little beyond such edge, as shown by the full lines in Figure 1, so that in the closing of the door this projecting end will engage the door jamb and thereby cause the batten to be pushed lengthwise and thus into its lowered position into close contact with the 75 floor.

The batten is automatically controlled by means of a spring E that will act to raise it when the door is opened and the inner end of the batten freed from engagement with the door jamb. This spring is of the flat or leaf type and is formed as a loop, one leg E' of which is longer than the other leg E'', and the nature of which loop is to normally distend the legs. The bow of this 80 spring is fitted into a recess F formed in the door A at the top of the rebate B so that the longer leg E' projects below the recess and enters a slot G formed in the top of the batten C to receive it. The tendency of the 85 legs to spread will thus act to force the batten normally in the lengthwise direction necessary to lift it on its link connections D.

The closing of the door will cause the batten to be forced down against this 90 spring's action, as shown by the dotted lines in Figure 1, so that when the door opens, and the push of the door jamb on the batten end is removed, the spring leg E' will immediately act in a lever like manner to lift the batten.

The spring E is retained within the recess F by means of a staple loop H driven into the door so that its cross member extends over the face of the recess, outside the 105 spring.

I claim:

The combination, with a hinged door provided along its bottom edge with a rebate, of a solid batten disposed in the rebate with its outer face flush with the adjacent face of the door and capable both of rising-and-

falling movement and of endwise movement, said batten having a central, inclined slot which opens through its upper edge and said door face having a recess which alines with said slot; parallel-motion link connections between the batten and the door; and a looped spring mounted in said door recess and having legs of unequal length, the longer leg projecting loosely into said slot; said spring also embodying a connecting bow between said legs which tends to spread them apart so as to nor-

mally hold the batten in raised position in said rebate with one end projecting axially through the corresponding end of the rebate and beyond the hinged edge of the door, said projecting end adapted to strike against the adjacent portion of the door jamb when the door is being closed, thereby to force the batten inward and downward in 15 the rebate into engagement with the floor.

In testimony whereof, I affix my signature.

REGINALD BASHAM.
